Attorney

UNITED STATES PATENT OFFICE.

FORREST GLEN GRAVES, OF McCOOK, NEBRASKA.

SKATE SHARPENER.

Application filed April 17, 1922. Serial No. 553,471.

To all whom it may concern:

Be it known that I, FORREST G. GRAVES, a citizen of the United States, residing at McCook, in the county of Redwillow and State 5 of Nebraska, have invented a new and useful Skate Sharpener, of which the following is a specification.

This invention relates to sharpening devices, and more particularly to a sharpening device especially designed for sharpening skates or the like.

The primary object of the invention is to provide a device of this character operated over the runner of a skate by the 15 hands of the user, novel means being provided for preventing lateral movement of the sharpener during the sharpening operation to insure the runner being formed with a true edge.

20 Another object of the invention is to provide a device of this character which may be adjusted for use in connection with skate runners of various thicknesses.

A still further object of the invention is 25 to provide means for securing files of various widths to the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

40 Figure 1 is a plan view of skate sharpener constructed in accordance with the present invention, and showing a file as secured therein.

Figure 2 is an end elevational view of the body portion of the sharpener.

45 Figure 3 is a bottom plan view thereof.

Figure 4 is an elevational view taken at right angles to Figure 2.

Figure 5 is a sectional view taken transversely of the body portion and

50 Figure 6 is a sectional view taken on line 6-6 of Figure 4.

Referring to the drawing in detail, the device includes a body portion embodying opposed sections 5 and 6, each of which being formed preferably of cast metal and 55 provided with adjacent runner engaging surfaces 7, which are relatively wide to contact with a skate runner throughout substantially the entire width of the runner.

Secured to the section 5 of the body portion are pins 8 which extend laterally from the runner engaging surface thereof, and are designed to move in the openings 9 formed in the opposed section 6, whereby the sections may be adjusted towards and 60 away from each other to vary the distance of space between the sections to accommodate runners of various thicknesses.

Each section is formed with a cut out portion or file receiving opening 10, the 70 openings of the sections being disposed directly opposite each other to align for the reception of a file as indicated in dotted lines in Figure 1 of the drawings.

A bar 11 extends over each cut out portion and is formed with a suitable threaded opening to accommodate set screws 12, which set screws may be moved into engagement with a file positioned in the file receiving openings for securing the file against 80 movement relatively to the body portion of the device.

In the use of the device, a file is positioned in the file openings of the section, the sections are then moved to the proper distance 85 apart to receive the skate runner to be sharpened. The set screws 12 are now operated, to secure the file in position, whereupon the sections are prevented from moving with respect to each other.

With the sharpener properly adjusted, the device is moved longitudinally of a skate runner, the file carried thereby contacting directly with the surface engaging portion of the runner to sharpen the same.

Having thus described the invention, what is claimed as new is:

In a skate sharpening device, a body portion including opposed sections, said sections adapted to move with respect to each other, said sections having file receiving openings, set screws carried by the sections

and adapted to engage a file positioned in the file receiving opening to hold the sections in spaced relation with each other, the space between the adjacent walls of the opposed section providing a clearance to permit a skate blade to be passed therebetween.

In testimony that I claim the foregoing

as my own, I have hereto affixed my signature in the presence of two witnesses.

FORREST GLEN GRAVES.

Witnesses:

J. L. BOHANNON,
P. R. MOATS.
